United States Patent Office

Des. 203,250
Patented Dec. 21, 1965

203,250

REVERSIBLE VEST

Maurice H. O'Link, St. Cloud, Minn., assignor to Stearns Manufacturing Co., St. Cloud, Minn., a corporation of Minnesota

Filed Oct. 22, 1964, Ser. No. 82,277

Term of patent 14 years

(Cl. D3—4)

FIG. 2

FIG. 1

FIG. 1 is a front perspective view of a reversible vest showing my new design;

FIG. 2 is a rear perspective view thereof; and

FIG. 3 is a perspective view thereof in opened and extended condition.

I claim:

The ornamental design for a reversible vest, as shown.
